UNITED STATES PATENT OFFICE.

DEMAS L. AULD, OF COLUMBUS, OHIO.

DESIGN FOR A BADGE.

SPECIFICATION forming part of Design No. 20,528, dated February 24, 1891.

Application filed October 18, 1890. Serial No. 368,717. Term of patent 7 years.

To all whom it may concern:

Be it known that I, DEMAS L. AULD, a citizen of the United States, residing at Columbus, in the county of Franklin and State of Ohio, have invented and produced a certain new and useful Design for Badges, of which the following is a specification, reference being had to the accompanying drawings, forming part thereof.

10 The accompanying print represents a face view of the badge, this view being deemed necessary to fully illustrate my design.

15 The leading features of my design consist in the representation of a railway hand ticket-dating stamp in a facing or background of suitable contrasting color, the whole appearing within a disk.

20 *a* represents the hand ticket-dating stamp, and *a'* is the representation of a coupon-ticket resting between the stamp-jaws and depending therefrom. This ticket is preferably outlined in a color and shape contrasting with its body. Surrounding this stamp is represented a circle or ring *c*. Between said hand-stamp and circle *c* a space is left which I may utilize for lettering. Projecting at regular intervals from the circle *c* are radial star-points *d*. Projecting from said circle *c* between the star-points *d* are ornamental projections or wings 25 *e*, the outer edge of each of which is notched

30 to form a wide V, said notch being filled approximately by scroll or similar ornamental work. The outline of these wings and their filling or bodies are of contrasting color or shade, as shown. The outer print of each of the wings *e* is provided with a rounded head *e'*. Projecting upwardly from the upper side of the circle *c* and extending across the center of the upper wing *e* is the representation of the head or jaws *f* of a ticket-punch, the curved handle ends *f* of which project from the lower side of the circle *c* and cross the two lower wings *e*.

35 With the exception of slight indentations and shallow lines used in the production of the 40 ornaments and figures represented, the face of the badge is approximately level or smooth.

45 The ornamental parts which project, as described, from the circle *c* or body of the badge are of such uniform length and arrangement 50 as to give the entire badge a general disk shape.

55 What I claim, and desire to secure by Letters Patent, is—

The design for a badge, as herein shown and described.

DEMAS L. AULD.

In presence of—

C. C. SHEPHERD,

BARTON GRIFFITH.
